UNITED STATES PATENT OFFICE

EARL STUMP, OF CHICAGO, ILLINOIS, ASSIGNOR TO ROBERTS AND SCHAEFER COMPANY, OF CHICAGO, ILLINOIS, A CORPORATION OF ILLINOIS

CLASSIFYING TABLE

Application filed December 13, 1929. Serial No. 413,715.

This invention relates to a material separating plant. In the form illustrated herewith it is shown as applied to a coal cleaning table in which coal is cleaned and separated from refuse and foreign matter. The invention is not limited to this application but for convenience it is shown in connection with this dry cleaning table or drying classifier. It has for one object to provide automatic means whereby the supply of air to the cleaning table is automatically controlled in response to the feed of material to the table itself. One object of the invention is, therefore, to cause the material to control the supply of air. Another object is to provide a mechanism whereby the quantity or the speed of the flow of material to the table will vary and control the quantity of air supplied to the table.

Other objects will appear from time to time in the course of the specification and claims.

The invention is illustrated in the figure more or less diagrammatically. The figure is a side elevation of an air cleaning table assembly with parts in section and parts omitted.

A indicates an air conduit by means of which air is supplied to a funnel-shaped member A¹ from which it is discharged through the cleaning surface A² of the table.

B is a butterfly valve fixed to a shaft B¹ which is controlled by a lever B². Rotation of the shaft moves the valve and so controls the supply of air to the entire assembly. The parts are normally so shaped that when the automatic control is in operation the valve will be slightly open at all times and thus some air will constantly be passing into the conduit and through the surface of the table.

C indicates a feed trough or chute by means of which material such as coal will be fed to the cleaning table.

I shall now describe the automatic separating means whereby the butterfly valve is moved to control the supply of air to the table in response to the feed of material to the table.

D is a link pivoted as at D¹ at its lower end and joined as at D² at its upper end to a lever

arm D³. D⁴ is a second link fastened to the lever arm D³ at a point separated from its pivoted point. D⁵ is a link member fastened at one end adjacent the outer end of the lever B² and fastened at its upper end to the lever D³, preferably between the points D² and D⁴. D⁶ is a second lever arm attached to the pivotally mounted shaft D⁷ and being connected at one end to the link D⁴ and carrying adjacent to its other end a counter weight D⁸. D⁹ is a switch adapted to be contacted by the end of the lever D⁶ when it is raised. The switch D⁹ is normally arranged to control the operation of the jiggling or moving mechanism for the table, so that when the switch is in one position jiggling movement of the table is carried out by the appropriate mechanism for that purpose and when it is thrown into another position by the action of the lever arm D⁶, the jiggling mechanism is thrown out of operation and the motion of the table is stopped. D¹⁰ is a gate attached to the pivotally mounted shaft D⁷ and extending into the path of material flowing downwardly along the chute C onto the table. Material, as it flows downwardly, strikes the gate D¹⁰ and swings it outwardly.

The use and operation of my invention are as follows:

When the device is in operation the parts will be more or less as shown. The means for moving the table is active and the table is in motion. Air is supplied from below and passes upward from the table. Material moves downwardly along the feed trough or chute, passes outwardly across the table and under the influence of the air and the motion of the table is separated and classified. The particular details of this action form no part of the present invention and will not be further described. It is sufficient to state that the material is separated and classified and cleaned by the action of the table.

When the material is being fed toward the table with sufficient speed and in sufficient quantities, the gate flap is held open. This rotates the shaft D⁷ counter-clockwise and moves the free end of the lever D⁶ away from the switch, thus raising the opposite end of the lever D⁶, raising the link D⁴, rais-

ing the left hand end of the lever D^8 , the link D^6 and the left hand end of the lever B^2 and so rotating the shaft B^1 and the valve B which is attached to it, in a clockwise direction and thus opening the valve. When the feed of material runs more or less constant, both as to quantity and speed, the condition of balance will be reached and a constant supply of air will be furnished to the table. 10 Variation in the speed, quantity or type of material which is fed to the table will cause a movement of the gate D^{10} and through the linkage above described will cause movement of the valve either to increase or decrease the supply of air. As the feed is reduced, the gate moves again in a clockwise direction and the valve is partially closed. If the feed is entirely stopped, the movement of the gate is sufficient to shut off all but a minimum of 15 the air and also to permit the lever arm to strike the switch and stop the operation of the jiggling or table moving mechanism.

It is desirable to prevent a complete clearing of the table, that is to say, to prevent a 20 complete discharge of all material from the table. Parts are so proportioned, therefore, that the switch which controls the table driving mechanism will be operated to cut off that mechanism before the feed of material to the table has completely stopped. Even though the feed may have completely stopped and the motion of the table has been stopped, it is desirable to keep the bed of 25 material which remains on the table in motion. Among other reasons, this is done to keep the cloth of the table dry. For that reason the parts are so proportioned that the valve cannot automatically be completely closed and at its minimum setting it is slightly open so that sufficient air can pass through 30 to keep the material which remains on the table in motion.

The mechanism which I have described above will act in response to variation of 45 the feed, the quantity of the feed and the speed of the feed. If the quality of the material fed remains the same as to size and dryness no substantial variation of the position of the air controlling valve will take 50 place. If the quantity of the material changes while the dryness and size of the material remains the same, a variation in the setting of the valve will be caused automatically. 55 If the quantity and the size of the material remain the same but the relative dryness is changed, the speed of the flow of material will be altered since wet material flows more slowly than dry material and this 60 change of speed will cause a change in the position of the gate D^{10} and correspondingly by means of the mechanism of links and lever, will cause a change in the air valve setting. Thus the material, as it is fed, 65 automatically controls the air fed in response

to changes either of the speed or material, its quantity or its quality.

I claim:

1. In combination with a material classifier, a continuous air supplying means therefor for forcing a constant supply of air through the classifier, means for feeding material thereto and regulating means to vary the volume of said air supply, adapted to operate automatically in response to variations 70 in the feed of material to said classifier whereby the supply of air is adjusted in accordance with requirements on the classifier table due to variations in the feed of material thereto, said regulated means arranged to 75 permit a minimum of air to pass, irrespective of its setting.

2. In combination with a material classifying table, means for giving it motion, means for supplying air continuously to it, means 85 for supplying material to be classified to it and means, responsive to variations in said material supply, adapted to vary the quantity of air and to stop the mechanism for moving 90 the table.

3. In combination with a material classifying table, means for giving it motion, means for supplying air continuously to it, means for supplying material to be classified to it and means, responsive to variations in said 95 material supply, adapted to vary the quantity of air and to stop and start the mechanism for moving for moving the table.

4. In combination with a material classifying table, means for giving it motion, means 100 for supplying air to it and for forcing air through it, means for supplying material to be classified to it and automatic means, responsive to variations in said material supply, adapted to vary the quantity of air and 105 to stop and start the mechanism for moving the table.

5. In combination with a material classifying table, means for giving it motion, means for supplying air to it, means for supplying 110 material to be classified to it and means, responsive to variations in said material supply, adapted to vary the quantity of air and to stop the mechanism for moving the table, the air supply being never reduced below a 115 fixed minimum.

6. In combination with a material classifying table, means for giving it motion, means for supplying air to it, means for supplying material to be classified to it and means, responsive to variations in said material supply, adapted to vary the quantity of air and 120 to stop and start the mechanism for moving the table, the air supply being never reduced below a fixed minimum.

7. In combination with a material classifying table, means for giving it motion, means for supplying air continuously to it and for forcing air through it, means for supplying material to be classified to it and automatic 130

means, responsive to variations in said material supply, adapted to vary the quantity of air and to stop and start the mechanism for moving the table, said control including a member contacting, and adapted to be positioned by, the material as it is fed to the classifier.

8. The combination with a material classifying table, means for forcing a constant supply of air through the classifier, means for supplying material to be classified to it and means, responsive to variations in said material supply, adapted to vary the quantity of air supplied to the classifier table whereby the air supply is adjusted in accordance with requirements on the classifier table due to variations in the feed of material thereto, said last means being arranged to prevent the reduction of air flow below a fixed minimum.

20 Signed at Matoka, county of Mercer and State of West Virginia, this 15th day of November 1929.

EARL STUMP.
